UNITED STATES PATENT OFFICE.

CHARLES E. MORRIS, OF LEAVENWORTH, KANSAS, ASSIGNOR TO CHARLES W. PARKER, OF LEAVENWORTH, KANSAS.

ROCKING TOY.

1,414,785.

Specification of Letters Patent. Patented May 2, 1922.

Application filed June 7, 1920. Serial No. 387,060.

To all whom it may concern:

Be it known that I, CHARLES E. MORRIS, a citizen of the United States, residing at Leavenworth, in the county of Leavenworth 5 and State of Kansas, have invented a certain new and useful Improvement in Rocking Toys, of which the following is a specification.

My invention relates to improvements in 10 rocking toys.

The object of my invention is to provide a rocking toy which is cheap to make, durable and not liable to get out of order, which simulates a walking animal and which will 15 afford exercise and amusement.

The novel features of my invention are hereinafter fully described and claimed.

In the accompanying drawing, which 20 illustrates the preferred embodiment of my invention,

Fig. 1 is a side elevation, partly broken away, of my improved rocking toy, having a form simulating a duck.

Fig. 2 is a top view of what is shown in 25 Fig. 1.

Fig. 3 is a front elevation of the toy.

Fig. 4 is a side elevation showing another position of the toy.

Similar reference characters designate 30 similar parts in the different views.

1 designates the body of the toy which may be a representation of any animal and which in the drawing simulates a duck.

Adapted to support the body are one or 35 more front legs 2, each having a rocker foot 3 having the usual arcuate supporting surface of a rocker.

At the rear of the legs 2 are one or more legs 4, each preferably, having a substantially flat foot 5. The legs 4 are pivoted to the body 1 by a transverse bolt 6, which, preferably, is at the rear of the legs 2 and in a vertical plane at the rear of the forward ends of the feet 5.

45 The legs 4 are respectively mounted in recesses 7 extending upwardly from the under side of the body 1. In the rocking of the toy, the rear edges of the legs 4 are adapted to bear against the rear surfaces 8 50 of the recesses 7.

Supported by the body and preferably mounted on the upper sides of the rocker feet 3 is a transverse bar 9 having in its upper side two notches 10 which form stirrups for receiving the feet of the rider. 55

Attached to the body 1 near its upper front portion, and preferably secured respectively to opposite sides of the neck 11 are two hand holds 12.

13 designates a lower jaw which is pivoted 60 by a transverse pin 14 to the head 15, the pivotal arrangement being such that the jaw will open and close when the toy is rocked.

In the operation of my invention, the rider sits on the body 1 with his feet resting in the 65 stirrups 10 and his hands grasping the hand holds 12, the parts being in the position shown in solid lines in Fig. 1.

If now the rider leans backwardly and pulls rearwardly on the hand holds 12, his 70 weight will be supported by the feet 5 and the rocker feet 3 will be lifted from the floor, upon which the legs 4 will, due to the weight of the rider, force the body and legs 2 forwardly until the parts assume the position 75 shown in dotted lines in Fig. 1. If now the rider leans forwardly, and presses forwardly on the hand holds 12, the body will have the weight transferred to the rocker feet 3 and the rocker feet will rock to the position 80 shown in Fig. 4, thereby lifting the bolt 6 and permitting the legs 5 to swing by gravity to the position shown in Fig. 4, in which position the feet 5 will strike the feet 3, thus limiting the forward swinging of the legs 4. 85 The rider then rocks backwardly to the position shown in solid lines in Fig. 1.

By repeating the sequence of operations just above described the toy will be caused to walk forward step by step with a rocking 90 motion.

I do not limit my invention to the structure shown and described, as many modifications, within the scope of the appended claims, may be made without departing 95 from the spirit of my invention.

What I claim is:—

1. A rocking toy having a body adapted to support a person, means for rockingly supporting the body, the body having a por- 100

tion simulating an animal's head, the head having a pivoted jaw arranged to swing to an open and shut position when the body is rocked, substantially as set forth.

5 2. A rocking toy having a body provided with a rocker foot, a leg pivoted to the body and having a foot at the rear of said rocker

to limit the forward swinging of said leg, the foot of the leg having a flat straight bottom surface, substantially as set forth.

In testimony whereof I have signed my name to this specification.

CHARLES E. MORRIS.
